Stoll

United States Patent Office.

JAMES SHERLOCK, OF NEW YORK, N. Y.

Letters Patent No. 93,130, dated July 27, 1869.

IMPROVEMENT IN KNAPSACK-ATTACHMENTS.

The Schedule referred to in these Letters Patent and making part of the same.

To whom it may concern :

Be it known that I, JAMES SHERLOCK, of the city, county, and State of New York, have invented certain new and useful Improvements in Attachments for Carrying Knapsacks, Haversacks, and other accoutrements; and I hereby declare the following to be a full, clear, and exact description of the same.

It is well known that the straps by which the knapsack, cartridge-box, and other accoutrements carried by the soldier, are attached to the person, are very defectively arranged, cramping and binding the breast and arms, and exercising an extremely injurious effect upon the vital organs; and, furthermore, that the load is very unevenly distributed, the greater portion, if not all of it, hanging from the back, and requiring the bending forward of the body, in order to preserve the equilibrium, and keeping the muscles in a constant state of tension, in order to properly sustain the weight.

These evils have long been felt, and the importance of some means whereby they may be removed is universally recognized, and the object I have in view is to furnish a ready and convenient means for the purpose.

The nature of my invention will be readily understood by reference to the accompanying drawings, in which—

Figures 1, 2, and 3, represent front, side, and rear views, respectively, of the different accoutrements and straps, as they appear when applied to the person.

In the present instance, the basis of the system of attachments is the cartridge-box belt *a*, which passes around the neck and rests upon the shoulders, hanging down in front, so as to carry the cartridge-box *A*, which occupies the position on the person shown in fig. 1, this position being that which is now considered by many the best for all purposes in actual service.

The waist-belt *b* passes through loops formed in the rear of the cartridge-box, and is fastened around the waist in the usual manner.

In order to attach the knapsack, without compressing the chest or binding under the arms, I provide the cartridge-box strap, on each side, with a ring, or equivalent holding-device, *c*, which is arranged, as shown in the drawings, so as to connect the divided strap *a*, and to these rings the knapsack-straps are attached.

To this end, on each side of the knapsack *B* are top and bottom straps *d e*, each provided, at or near its end, with a hook, *f*.

In attaching the knapsack to the person, the upper straps are passed over the shoulders, and their hooks *f* are caught over the upper part of the rings *C*. The lower straps are then brought up, and their hooks are also caught over the lower part of the rings, as indicated in dotted lines, fig. 2.

An inspection of the drawing is all that is needed,

without further explanation, to demonstrate that the chest is left free and unconfined, and that the straps cannot in any manner bind or cramp the arms, or interfere with free movement of the person. Moreover, the coat can readily be unbuttoned and thrown open, which, under the old system of strapping, is impracticable.

Another advantage gained by thus attaching the knapsack to the cartridge-box strap, instead of strapping it directly to the person, is that the weight of the box, which, when filled with the proper supply of cartridges, is considerable, serves to counterbalance, to a very appreciable extent, the weight of the knapsack.

In order to still further counterbalance the knapsack, and to distribute equally the weight, as well as to furnish a convenient means of attaching the haversack, canteens, &c., I extend the ends of the knapsack-straps beyond the points where the hooks *f* are attached, and furnish these ends with loops or rings *h*, in which are caught the snap-hooks *k*, on the end of the canteen-straps, and like hooks *l*, on the haversack-straps.

The position occupied by the canteens *C*, which I prefer to use in pairs, is shown clearly in fig. 1.

I find it convenient, also, to use a pair of haversacks, *D*, which occupy the position on the person shown in figs. 2 and 3.

The strap or straps by which they are suspended may be long enough to pass under the arms and over the shoulders, if the weight of the articles contained in them be sufficiently great to make this mode of carrying them more comfortable, but ordinarily it will be sufficient to use the hooks *l*, as shown.

The two haversacks are connected in rear by a hook and ring, *m n*, as shown in fig. 3, so that one haversack may be disengaged from the other, and brought around to the front, whenever necessary.

This mode of constructing and arranging the haversacks will be found convenient and advantageous in many respects.

It will be, of course, understood, that while specifying the use of rings and hooks, I can make use of any other suitable fastening-devices for the purpose. I prefer, however, the use of the devices named, as they admit of the accoutrements being secured to or removed from the person with the utmost facility and dispatch.

It will also be understood that the straps are constructed and provided with buckles, &c., in the usual manner, so that they may be adjusted to the size of the person using them. By lengthening or shortening the straps of the canteens, haversacks, &c., their weight may be so adjusted, as, in connection with the cartridge-box, to counterbalance quite accurately the weight of the knapsack.

For such duty as does not require the use of all the

accoutrements, the soldier can hang the cartridge-box strap over one shoulder, in the usual manner, and the knapsack may be then secured also in the usual manner, by catching the lower hooks *f* in the rings *h*.

Having now described my invention, and the manner in which the same is or may be carried into effect,

What I claim, and desire to secure by Letters Patent is—

1. The combination of the cartridge-box, divided cartridge-box strap, and connecting-rings, with the knapsack, knapsack-straps, and supporting-hooks, under the arrangement shown and specified.

2. The two haversacks, when constructed, arranged, and connected with each other, and with the straps

from which they are suspended, substantially in the manner shown and set forth.

3. The arrangement, upon the person of the wearer, and with relation to each other, of the knapsack, cartridge-box, canteen or canteens, and haversacks, and straps or attachments, whereby the same are held in place, substantially as herein shown and specified.

In testimony whereof, I have signed my name to this specification, before two subscribing witnesses.

JAMES SHERLOCK.
